(57) **CLAIM**

The ornamental design for a combined panel skirt and photovoltaic panels, as shown and described.

DESCRIPTION

FIG. 1 is a top front perspective view of a combined panel skirt and photovoltaic panels showing our new design;

FIG. 2 is a top view thereof;

FIG. 3 is a front view thereof;

FIG. 4 is a right side view thereof; and,

FIG. 5 is a left side view thereof.

The broken lines in the figures show portions of the panel skirt and photovoltaic panels that form no part of the claimed design.
